UNITED STATES PATENT OFFICE.

GUSTAV J. GRUENDLER, OF CLAYTON, MISSOURI.

REFRIGERANT CONTAINER.

Application filed August 2, 1926. Serial No. 126,655.

My invention relates to refrigerant containers and more particularly to refrigerant containers such as are used with complementary cooling apparatus to cool the interior of refrigerators.

Heretofore when a refrigerant container was adapted to be filled with brine and was cooled by a cooling coil of any of the well known types in which certain chemicals are first compressed and then allowed to expand in the coil the brine was a dead body which did not circulate or move and consequently although the brine around the cooling coil was cooled the temperature of the entire body of brine was not lowered very much and the walls of the container remained comparatively warm. Further, if the refrigerant container was made with a plurality of spaced sections so that with a given outside dimension a maximum area of cooling surface could be obtained, the coil was usually placed in one of the sections and no adequate means was provided whereby when the brine in that section having the cooling coil therein was cooled it was allowed to flow into the other sections to equalize the temperature throughout the whole container. Also, in refrigerant containers of this type no adequate means for allowing a rising and falling of air through the container has been provided.

The objects of my invention are to provide a refrigerant container more particularly adapted for use with a cooling coil and constructed and arranged whereby a circulation of brine throughout the whole container is allowed; and to provide a refrigerant container in which a vertical and horizontal circulation of air throughout the whole container is provided.

My invention is fully shown in the accompanying drawings wherein Figs. 1 and 2 are a plan and elevation, respectively; Fig. 3 is a section along the line 3-3 of Fig. 1; Fig. 4 is a section along the line 4-4 of Fig. 1; and Figs. 5 and 6 show a modified form of the refrigerant container. In order that the parts may be clearly shown the containers are not shown filled with brine although they are filled when in operation as explained below.

Referring to the figures, both forms of refrigerant container shown therein as embodying my invention are preferably made of metal, are arranged to be substantially filled with brine and have an upper

portion 1 open at the top and a lower portion divided into a plurality of legs extending downwardly from the upper portion. In each of the embodiments shown there are 60 downwardly extending side legs 2 and an intermediate leg 3. These legs are closed at their lower ends so that the brine in the refrigerant container will be held therein and are, preferably, spaced apart to form air 65 spaces 4 extending through the refrigerant container as clearly shown in the figures. The air spaces are open along the bottom of the container, have their sides formed by the walls of adjacent legs, and have the upper wall 4^a thereof positioned substantially midway the top and bottom of the refrigerant container. Positioned in the upper portion 1 is a cooling coil 5 with the coil pipes 6 thereof extending downwardly in the intermediate leg 3. The cooling coil 5 has the face plate 7 which is fastened onto the front wall of the refrigerant container, preferably, by means of the bolts 8. This cooling coil is connected to a compressor of any of the usual types, not shown, by means of the pipes 9. Ammonia or any one of several other chemicals after being compressed flows into the cooling coil through the intake pipe, is allowed to expand in the coil pipes 6 and 75 then returns to the compressor through the outlet pipe of the cooling coil.

A plurality of air ducts 10 lead through the upper portion 1 into the air spaces 4. In these embodiments of my invention the air 80 ducts are arranged substantially vertically and have the upper ends thereof terminating just below the top of the refrigerant container but above the normal level of brine in the container which is as indicated by the 85 dotted lines in Figs. 2, 3, 4, 5 and 6. The lower end of the ducts 10 opens through the upper wall 4^a of the air spaces 4. Braces 11 extending between adjacent air ducts 10 and between the end air ducts and the side walls 100 of the upper portion 1 may be provided to prevent the air ducts from being bent out of position by any slight shock or movement of the brine in the container.

Passages are provided between the downwardly extending legs 2 and 3 and these passages provide communication between the legs to allow a flow of brine from the intermediate leg 3, preferably from the lower end thereof, into the adjacent legs, all for the 105 purpose more fully hereinafter set forth. In these embodiments of my invention these

passages are in the form of tubes 12 extending between adjacent legs and arranged as shown in the figures. I prefer that a plurality of tubes be provided.

- 5 In the form of my invention shown in Figs. 1 to 4, inclusive the coil pipes 6 extend into the intermediate leg 3 for only a portion of their length. In the modified form of my invention shown in Figs. 5 and 10 6, the air spaces 4 extend further towards the top of the refrigerant container so that substantially the entire length of the coil pipes 6 is positioned and extends downwardly in the intermediate leg 3, as shown.
- 15 The use and operation of a refrigerant container embodying my invention is as follows:

After a container has been filled with brine to the point indicated, the cooling coil 20 5 is started in operation, and, since the coil is positioned in the upper portion 1 and the intermediate leg 3 and extends downwardly in this leg, the brine in the intermediate leg 3 will be cooled first and as the brine is 25 cooled it will drop downwardly in the leg and when it has reached substantially the lower end thereof will pass outwardly through the tubes 12 into the side legs 2. The comparatively warm brine in the upper 30 portion of the side legs 2 will be forced upwardly by this movement and the brine at the top of the side legs in the upper portion 1 will move inwardly towards the space above the intermediate leg 3 where it is cooled by 35 the cooling coil 5, and this brine then moves downwardly in the intermediate leg 3 to complete the circulation. It will be readily seen that a circulation of the brine is set up 40 downwardly in the intermediate leg 3, outwardly through the tubes 12, upwardly in the side legs 2, and inwardly at the top of the side legs into the intermediate leg 3, with a resultant equalization of the temperature 45 of the brine in the container. As the brine in the container is cooled and, in turn, the walls of the refrigerant container are cooled the air in the refrigerator in which the refrigerant container is placed will be cooled and will fall downwardly around the refrigerant container and some of the air above 50 the refrigerant container will pass downwardly through the air ducts 10 into the air spaces 4 during which passage it will be cooled by the walls of the air ducts 10 and 55 it will also be cooled by the adjacent walls of the downwardly extending legs at either side of the air spaces 4.

As set forth above by this operation a moving body of brine is created in the refrigerant container and the low temperature of the cooling coil 5 is thereby conducted to the metallic walls of the container.

It may be readily seen that the details of construction of a device embodying my in-

vention may be varied in arrangement, size 65 and shape within wide limits without deviating from the spirit of the claims included below.

What I claim as new and desire to secure by Letters Patent, is:

70 1. A refrigerant container for refrigerators comprising a plurality of vertically disposed legs adapted to contain brine, means in one of said legs for cooling the brine therein, and means whereby the brine may flow from substantially the lower end of said leg in which the brine is cooled into the other of said legs.

75 2. A refrigerant container for refrigerators comprising an upper portion with a plurality of spaced legs extending downwardly therefrom, said legs being adapted to contain brine, a cooling coil positioned in said upper portion and extending downwardly into one of said legs, and said legs having communicating passages for the flow of brine therebetween.

80 3. A refrigerant container for refrigerators comprising an upper portion with a plurality of legs extending downwardly therefrom, said legs being adapted to contain brine and being spaced apart to form an air space extending through said container, a cooling coil extending downwardly in one of said legs to cool the brine therein, and one 85 or more tubes extending between said legs and arranged whereby brine may flow from the lower end of said leg having the cooling coil therein into the other of said legs.

90 4. A refrigerant container for refrigerators comprising an upper portion with three legs extending downwardly therefrom, said legs being spaced apart to form a plurality of air spaces extending through said container, a cooling coil positioned in the intermediate of said legs, and a plurality of tubes extending between the lower end of said intermediate leg and the leg at each side thereof and arranged so that brine may flow from said intermediate leg into the 95 other of said legs.

100 5. A refrigerant container for refrigerators comprising a plurality of spaced legs, said container being adapted and arranged to provide communication between said legs at the upper and lower ends thereof, and a cooling coil positioned in one of said legs to cool the brine therein.

105 6. A refrigerant container for refrigerators comprising three spaced legs, said container being adapted and arranged to provide communication between said legs at the upper and lower ends thereof and a cooling coil positioned in the intermediate of said legs.

110 In witness whereof I have signed my name to this specification.

115 GUSTAV J. GRUENDLER.
